UNITED STATES PATENT OFFICE.

RUDOLPH ADE, OF EVANSVILLE, INDIANA, ASSIGNOR TO EVANSVILLE TOOL WORKS,
OF EVANSVILLE, INDIANA, A CORPORATION OF INDIANA.

TOOL-HANDLE-HOLDING MEANS.

Application filed August 11, 1923. Serial No. 656,882.

To all whom it may concern:

Be it known that I, RUDOLPH ADE, a citizen of the United States, residing at Evansville, Vanderburg County, Indiana, have invented certain new and useful Improvements in Tool-Handle-Holding Means, of which the following is a specification.

The present improvements relate to means for holding a handle to such a tool as a hammer, adze, etc., and will find its chief application in connection with such tools as have what is known as an adze-eye adapted to receive the handle.

In the accompanying drawings, which form a part of this specification, Figure 1 is a fragmentary view showing partly in substantially medial section an adze-eye type of claw hammer exemplifying these improvements; Fig. 2 is a cross-sectional view as on the line 2—2 of Fig. 1; and Fig. 3 is a fragmentary sectional view showing part of the structure of Fig. 1 after resetting the handle.

In such adze-eye tool heads there is a tubular extension as 10 of the main body through which, together with the main part of the head, the eye or handle opening extends. The extension 10 is designed to provide a relatively long handle opening whereby the handle may be secured to the head the more strongly. As shown by Fig. 1 the handle opening is provided with a constricted area as at 11, which is ordinarily about half-way from end to end of the opening or eye. The walls defining the handle opening converge to this constricted portion or area at 11 from both ends of the eye, such convergence being not only at the top and bottom of the eye, as shown in Fig. 1, but the opposite side walls similarly converge. The handle opening has a relatively long axis in the normally vertical direction in cross-view and a relatively short axis normally horizontal in cross-view. The adze-eye construction described is according to ordinary practice well understood.

The handle inserted in such tools is made with a part 12 on tapered lines adapted to fit into that portion of the eye defined by the projection 10. In ordinary practice a simple wedge or wedges as 13 are driven into the outer end of the handle, expanding the wood there so as to fit tightly against the outwardly enlarging walls defining that part of the handle opening, and thus the handle is more or less securely locked in the tool

head. Various other means than such simple wedges 13 have been suggested for expanding the outer end of the wood handle. It is immaterial to the present invention what means are employed in lieu of the simple wedges 13 shown, which are intended to illustrate means for expanding the outer end portions of the handle to lock that part of it in the tool head.

When the wood of the handle dries out it has been customary to drive the handle farther into the head, thus restoring the fit originally provided in the adze-eye extension 10, with the result that the handle is forced outwardly beyond the end of the head, and thereupon the wedging means, for instance the simple wedges 13, are driven in farther, thus fairly well restoring the fit of the handle in that part of the head, the projecting wood being thereupon removed.

Owing to the shocks and strains upon the handle at the head of such a tool as a hammer, and notably a claw hammer, and because of the shrinkage of the wood, such handles are constantly working loose. Play or looseness between the head and the handle soon develops, and this gradually increases through the strains tending to compress fibers of the wood, such looseness contributing to the loosening of the wedges, and according to usual practice considerable and frequent adjustment has been required, and the practice ordinarily includes such make-shifts as the driving in of nails or additional wedges from the outer end of the handle, substantially ruining the handle in the eye and necessitating a new handle.

The present improvements have for their principal object the provision of simple, cheap and easily applied means for overcoming the objection of loose handles in such tools, and the provision of means which may readily be operated to improve the holding effect from time to time, and which are equally advantageous at times when a resetting of the handle is desired.

To these ends I bore a hole 14 through the extension 10, about midway of its ends and preferably in the normally up-and-down direction of the tool, and at a side thereof easily accessible, such hole being parallel with the longest sides of the adze-eye opening, and having an axial line directed about midway between those sides, and after the part 12 of the handle is firmly driven into

the extension 10 and the wedging means as 13 applied, and after the handle is as securely held by such means as is ordinarily accomplished, I insert in the hole 14 preferably a cone-shaped wedge shown as a screw 15 which has preferably a cylindrical head adapted to pass into the opening 14 and through the same should occasion suggest, the screw having a tapered part 16 terminating preferably in a sharp point 17. The point 17 is first driven slightly into the handle through the hole 14 until the threads catch into the wood, and then the turning of the screw, as with a screw driver, causes the point 17 to penetrate between fibers of the wood, pressing them apart without unduly cutting them, and the screw as a whole thus acts as a wedge expanding the wood in that part of the eye defined by the extension 10. The result is that the wood in this part of the eye is made to contact the sides of the eye there very tightly. Owing to strains upon the handle, as, for instance, by using the claw thereof, the part 12 of the handle is apt to become somewhat loose even while the outer end portion of the handle is still held tightly. Such looseness may readily be overcome by advancing the screw, and such tightening may be continued from time to time as found desirable.

A time usually arrives in the history of every new hammer or tool of that general kind when, through the drying out of the handle, it is practically necessary to reset the handle, which is usually done without removing it from the head, as by forcing the handle farther into or through the head and readjusting the outer wedging means. According to these improvements the screw 15 is entirely withdrawn before such resetting operation, and before anything else is done a tapered wooden plug, partly shown at 20 Fig. 3, is driven into the hole in the handle formed by the screw 15. Thereupon the handle is driven into the head tightly, the wedge means, for instance the wedges 13, further tightened, thus resetting the handle according to prior practice, and there-

upon the screw 15 is reinserted, as shown in Fig. 3. After such resetting of the handle ordinarily no further resetting is required, but if it should be desirable to do so the entire resetting operation could be repeated. Ordinarily after such resetting the handle can be maintained tight by advancing the wedging means as 13 and also the screw 15.

The screw 15 not only serves as a wedge for expanding the handle in the extension 10, but it has the incidental function of locking the handle securely against retraction. I am aware that bolt-like members have heretofore been suggested for the latter purpose, but, so far as I know, means have not heretofore been suggested for providing an expansion of the handle in the adze-eye part 65 of the tool head. The means I have herein set forth are simple and effective and greatly improve the conditions for maintaining a satisfactory fit between the handle and head of such tools.

I contemplate as being included in this invention such changes, modifications and departures from what is specifically herein illustrated and described as fall within the scope of the appended claim.

I claim:

The combination of a tool head having a handle opening therethrough and having an extension providing as part of said opening an adze-eye of the character described having a relatively long axis and a relatively short axis in cross view, said extension having a hole therein for a wedge to extend therethrough in the direction of said relatively long axis, a wood handle in said handle opening, means for holding the outer end portion of the handle tightly in the outer portion of the handle opening, and a threaded cone-shaped wedge in said hole and extending into the handle, said wedge having a cylindrical head of a diameter permitting it to pass into said hole to provide for advancing the wedge from time to time by a threading action beyond its normal relative position.

RUDOLPH ADE.
